(57) CLAIM

The ornamental design for a beverage brewer, as shown and described.

DESCRIPTION

FIG. 1 is a front isometric view of a beverage brewer showing a further variant of my new design, with a cup tray in the deployed position;

FIG. 2 is a rear isometric view of the beverage brewer of FIG. 1;

FIG. 3 is a left side elevation view of the beverage brewer of FIG. 1;

FIG. 4 is a front elevation view of the beverage brewer of FIG. 1;

FIG. 5 is a right side elevation view of the beverage brewer of FIG. 1;

FIG. 6 is a rear elevation view of the beverage brewer of FIG. 1;

FIG. 7 is a top plan view of the beverage brewer of FIG. 1; FIG. 8 is a bottom plan view of the beverage brewer of FIG. 1; and,

FIG. 9 is a front isometric view of the beverage brewer of FIG. 1, with the cup tray in the retracted position.

The broken lines in the drawing depict portions of the beverage brewer that form no part of the claimed design.
